UNITED STATES PATENT OFFICE.

CLARK P. DEY, OF KEYSTONE, WASHINGTON

COMBINED RAILROAD TIE AND CLAMP.

No. 869,070.

Specification of Letters Patent.

Patented Oct. 22, 1907.

Application filed February 18, 1907. Serial No. 357,986.

To all whom it may concern:

Be it known that I, CLARK P. DEY, a citizen of the United States, residing at Keystone, in the county of Adams and State of Washington, have invented certain new and useful Improvements in Combined Railroad Ties and Clamps, of which the following is a specification.

The present invention relates to a combined railroad tie and rail clamp, the object being to provide an improved tie which will prove durable and economical in use and which carries a novel form of clamp by means of which the rails are rigidly connected to the tie, but are permitted to have the required lateral adjustment for gaging the road.

For a full understanding of the invention and the merits thereof and also to acquire a knowledge of the details of construction and the means for effecting the result, reference is to be had to the following description and accompanying drawings, in which:

Figure 1 is a perspective view showing the invention applied. Fig. 2 is a vertical longitudinal sectional view.

Corresponding and like parts are referred to in the following description and indicated in all the views of the drawings by the same reference characters.

A tie constructed in accordance with the present invention has a hollow formation and is designed to be formed from a single elongated piece of sheet metal, the longitudinal edge portions of the sheet being bent upwardly and inwardly to form the inclined sides 1 of the tie, and being then bent inwardly to form the overlapping portions 2 constituting the top of the tie. These overlapping portions 2 are rigidly connected by means of the rivets 4 which are preferably arranged in pairs as shown in the drawings and extend from one end of the tie to the opposite end.

The clamping means for positioning the rails comprises a base plate 5 and a pair of clamping members 6 adjustably connected to the base plate. In the specific formation of the base 5 it will be observed that the same is in the nature of an elongated strip of material provided toward its opposite end portions with the transversely disposed ribs or teeth 7. One of the clamping members 6 is located upon each side of the rails, and these clamping members comprise the slotted plates 8 resting upon the base 5, the rail engaging ends of the slotted plates 8 being extended upwardly at 12° so as to fit over the base of the rail and hold the same securely in position. The lower faces of the slotted plates 8 are

formed with the downwardly projecting laterally disposed serrations 9 which are designed to engage the ribs 7 upon the base plate 5 and normally lock the clamping plate against sliding movement. Bolts 10 are employed for securing the base plate 5 to the top 2 of the tie, and these bolts also project through the slots 11 in the clamping members 6 and serve to connect the clamping members to the base plate 5. With this construction it will be readily apparent that by loosening the bolts 10 the slotted plates 8 can be lifted so as to remove the serrations 9 from engagement with the ribs 7 and can then be moved longitudinally in order to adjust the position of the rail. Attention is directed to the fact that the top 2 of the tie which normally receives and distributes the pressure exerted by the rails is composed of the overlapping edges of the sheet metal of which the tie is formed, the said overlapping edges mutually reinforcing each other and thereby producing a tie which will withstand considerable hard usage.

Having thus described the invention, what is claimed as new is:

1. In a device of the character described, the combination of a hollow tie formed of sheet material, the edges of which overlap at the upper portion of the tie, a rail clamp carried by the tie, and a fastening member securing the rail clamp to the tie and passing through the said overlapping edges of the sheet material.

2. In a device of the character described, the combination of a hollow tie formed of sheet material, the edges of which overlap at the top of the tie, and a rail clamp comprising a base plate and rail clamping members bearing against the base plate, bolts being employed to secure the base plate to the overlapping edges of the sheet metal of which the tie is formed and the said bolts also serving to adjustably connect the rail clamping members to the base plate.

3. In a device of the character described, the combination of a hollow tie formed of sheet material and comprising inclined sides and a top formed by the overlapping edges of the sheet material, and a rail clamp comprising a base plate and rail clamping members bearing against the base plate, bolts being employed to secure the base plate to the top of the tie, and said bolts also serving to adjustably secure the rail clamping members to the base plate.

4. A tie formed of a single piece of sheet material and comprising inclined sides and a top somewhat narrower than the bottom and constituted by the overlapping edges of the piece of sheet material.

In testimony whereof I affix my signature in presence of two witnesses.

CLARK P. DEY. [L. S.]
